Primary Examiner — Janice Hallmark*(74) Attorney, Agent, or Firm* — NSIP Law(57) **CLAIM**

The ornamental design for a docking station for mobile phone, as shown and described.

DESCRIPTION

FIG. 1 is a front perspective view of a docking station for mobile phone showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a front perspective view thereof shown in a state of use.

Dash-dash broken lines illustrate portions of the docking station for mobile phone that form no part of the claimed design. Dot-dash broken lines illustrate the boundaries of the claimed design. Additional dash-dash broken lines in FIG. 8 showing a mobile phone illustrate environmental subject matter and form no part of the claimed design.
